Patented Dec. 16, 1975

238,105

REFILLABLE FLUID CONTAINER USED TO APPLY HEAT OR COLD FOR THERAPEUTIC PURPOSES

Edith C. Amend, 10 Maher Ave.,
Greenwich, Conn. 06830

Filed Sept. 17, 1973, Ser. No. 397,795

Term of patent 14 years

Int. Cl. D7—99

U.S. Cl. D83—1 P

T1Q.1.

T1Q.2.

FIG. 1 is a perspective view of a refillable fluid container used to apply heat or cold for therapeutic purposes embodying my new design;

FIG. 2 is a rear elevation thereof;

FIG. 3 is a front elevation thereof; and

FIG. 4 is an end view thereof as seen from the right of FIG. 3;

In FIGS. 1-3, the valve is shown in broken lines for illustrative purposes only.

I claim:

The ornamental design for a refillable fluid container used to apply heat or cold for therapeutic purposes, as shown and described.
